CLAIM

The ornamental design for a vegetable peeler, as shown, and described.

DESCRIPTION

FIG. 1 is a perspective view of the vegetable peeler;

FIG. 2 is a front elevation view thereof;

FIG. 3 is a rear elevation view thereof;

FIG. 4 is a side view thereof;

FIG. 5 is a top view thereof; and,

FIG. 6 is a bottom view thereof.

The broken lines represent unclaimed features and form no part of the claimed design.
